UNITED STATES PATENT OFFICE.

JOSEPH A. RICHTER, OF LOS ANGELES, CALIFORNIA.

RIGHT AND LEFT HAND PEELING KNIFE.

Application filed December 14, 1925. Serial No. 75,304.

This invention relates to fruit and vegetable paring implements and especially to a right and left hand tool.

An object of the invention is to provide a tool of a type having a handle to be grasped in the closed hand and having on one end an open seat along which may be laid a two-edged safety-razor blade which is exposed practically throughout the length of each cutting edge in such manner that either edge can be applied to and drawn along a fruit or vegetable to be pared or peeled.

Another object is to provide a device of utmost simplicity and of but three parts which are separable, excepting the blade.

Other objects and advantages will be made manifest in the following specification of an embodiment of the invention herewith illustrated; it being understood that modifications, variations and adaptations may be resorted to within the spirit and scope of the invention as here claimed.

Figure 1 is a perspective of the device as used.

25 Figure 2 is a top plan view.

Figure 3 is a cross-section on line 3—3 of Fig. 2.

Figure 4 is a bottom perspective of the blade bender.

30 Figure 5 is a perspective of the blade seat end of the handle.

Figure 6 is a plan of a two-edged safety razor blade.

The device comprises a stout handle 2 at 35 one end of which is a bed or seat 3 transversely convex on its top to receive a well known type of flexible, flat safety-razor blade B having longitudinal cutting edges and usually provided with three holes along its center.

The blade is applied to lie lengthwise along the seat 3 and its corners rest between upstanding shoulders 4 with the longer, sharp edges of the blade exposed over slots 45 5 along which extend side bars 6.

The edges of the blade B overhang the bars 6, see Fig. 3, for the whole length of the bars so that when the applied blade is drawn along a fruit or vegetable V, the paring readily slides between the blade and the bar. The underside of the body of the seat 3 inclines well inward and away from the bars thus allowing ready escape of the paring P.

To obtain the best action the blade is bent transversely to conform to the face of the seat by means of a simple concave clamp

member 10 having a central hole 11 for a screw 11 to pass through the center hole in the blade and screw into a tapped hole 12 in the seat body. The bender 10 has lugs 10* to pass through the other holes and into pockets 13 in the seat. This keeps the blade B from swinging around on the screw 11.

From the above it will be seen that old razor blades can be very effectively used by the house-wife, or others, as a means for fruit or vegetable paring purposes.

When the blade is clamped on it is bent transversely and presents straight cutting edges at the sides of the seat 3 and over the 70 bars 6 and slots 5.

The paring end of the implement has a 75 scooping or digging spoon 15 for removing specks, potato-eyes and deteriorations from the object being pared.

The invention claimed is:

1. A paring knife including a handle having integral therewith at one end a blade seat extending lengthwise of the handle and which is transversely crowned and has a central screw hole from its top downward, a razor blade applicable to the seat to extend lengthwise of the handle, side bars spaced along and below the crown of the seat and forming gages for cutting, a concave-faced clamp member to bend the blade to said seat, and a screw for clamping the parts together and threaded into said screw hole.

2. A paring knife including a handle 90 having integral therewith at one end a blade seat extending lengthwise of the handle and which is transversely crowned and has a central screw hole from its top downward, a razor blade applicable to the seat to extend lengthwise of the handle, side bars spaced along and below the crown of the seat and forming gages for cutting, a concave-faced clamp member to bend the blade to said seat, and a screw for clamping the parts together and threaded into said screw hole; said seat being generally depressed in its end of the handle.

3. A paring knife including a handle 105 having integral therewith at one end a blade seat extending lengthwise of the handle and which is transversely crowned and has a central screw hole from its top downward, a razor blade applicable to the seat to extend lengthwise of the handle, side bars 110 spaced along and below the crown of the seat and forming gages for cutting, a con-

cave-faced clamp member to bend the blade to said seat, and a screw for clamping the parts together and threaded into said screw hole; said seat being generally depressed in 5 its end of the handle, and having at the ends of said bars a set of upstanding lugs to shield the corners of the blade.

4. A paring knife having a handle at one end of which is a coaxial, generally oblong 10 body part having a depression in its top face, upwardly projecting lugs at corners of the depression, a safety razor blade lying

in the depression and whose corners are protected by said lugs, said depression having a transversely crowned surface, and a row 15 of apertures along the crown, and said body having slots longitudinally between side pairs of the lugs and over which the edges of the blade lie, a clamp plate having pins to pass through the blade and into certain 20 of said apertures, and a screw for forcing the plate down on and bending the blade transversely to fit the crown.

JOSEPH A. RICHTER.
